(57) **CLAIM**

The ornamental design for a scraper, as shown and described.

DESCRIPTION

FIG. 1 is a front perspective view of the scraper according to the present design;

FIG. 2 is a front view or rear view thereof;

FIG. 3 is a side view thereof;

FIG. 4 is a top view thereof;

FIG. 5 is a bottom view thereof; and,

FIG. 6 is a front view thereof showing the scraper joined to a broom handle.

The broken line showing of portions of the scraper element and the broom forms no part of the claimed design.
